BROAD FLEXIBLE NOZZLE FOR SOLE CEMENTING

Wilbur L. MacKenzie, Beverly, Mass., assignor to
United Shoe Machinery Corporation, Flemington, N. J., a corporation of New Jersey

Application April 30, 1947, Serial No. 745,061

4 Claims. (Cl. 91—43)

1
This invention relates to flexible nozzles for applying coating materials such as cement to shoe soles and especially to soles which have been molded.

The desirability of arranging the delivery outlets of a nozzle in oblique relation to the line of feed in order to apply a band of uniform width which shall be spaced at a uniform distance from the periphery of the sole has been explained in Letters Patent of the United States No. 2,293,209, granted August 18, 1942, upon my application. In that patent there is disclosed a form of flexible nozzle in which the adjacent plates or delivery fingers are made successively shorter so as to increase their inclination and position the tips and hence the line of outlet openings in echelon, obliquely to the line of feed, as viewed from above. This arrangement is highly successful where the band of cement to be applied is a fraction of an inch. If, however, as in the coating of platform soles, it is desired to apply a broader band which will coat substantially the whole of the attaching surface of the sole, it is found that the increasing inclination of the successive plates brings the innermost plate to a substantially vertical position and thus prevents upward yielding.

Accordingly, an object of the invention is to provide an improved nozzle construction enabling an oblique relation of the delivery openings to the line of feed in relatively wide nozzles.

In accordance with a feature of the invention, the echelon arrangement of the ends of the delivery members is obtained by mounting members of like lengths upon a pivot pin which is skewed with respect to the sides of the plates. This arrangement is obtained in the illustrated construction by enlarging the holes in the delivery plates in a horizontal direction so that the pivot pin will pass through them in a skewed relation and contact the plates only at the opposite corners of the holes. It will be observed that this reduces the cost of the nozzle substantially for the simple reason that the plates are identical.

These and other features of the invention will best be understood from a consideration of the following specification taken in connection with the accompanying drawings in which,

Fig. 1 shows a nozzle embodying the present invention mounted in a machine designed for the application of cement to shoe soles and viewed in side elevation;

Fig. 2 is an end elevation on an enlarged scale of the nozzle and its mounting;

Fig. 3 is a detail view of a single delivery plate in side elevation;

2
Fig. 4 is an angular view of the parts shown in Fig. 2;

Fig. 5 is a similar view of the work-engaging parts showing the nozzle resting upon the curved shank portion of a molded sole;

Fig. 6 is a view similar to Fig. 4 but viewing the nozzle from the rear; and

Fig. 7 is an enlarged view of the nozzle taken in horizontal section through the pivot pin of the delivery members.

The nozzle 10 is shown mounted upon a bracket 12 which is adjustably attached by a screw 14 to an outstanding arm 16. This arm is secured to the side of a machine frame 18 and acts as a journal for a shaft 20 at the outer end of which there is supported a feed roll 22. This feed roll is a disk-like member having oblique teeth 24 (Fig. 4) spaced to provide intermediate lands so that the teeth will not dig too deeply into the sole and yet will give a positive feed. A coating work supporting feed roll 30 is mounted at the end of a shaft 32 which is journaled in an arm 34 tiltably supported between pivot pins 36 mounted in inwardly extending lugs 38 on the machine frame. This arm 34 has an inward extension 40 for engagement by a treadle rod (not shown) to enable the supporting feed roll 30 to be lifted, thereby to raise a sole into engagement with the upper feed roll 22 and the nozzle. On the arm 34 there is also another supporting roll 42 and a gage 44.

This gage is of the type described in Letters Patent of the United States No. 2,073,647, granted March 16, 1937, upon the application of C. A. Newhall and it comprises a roll 46 which is engaged by the edge of the sole, a succeeding roll 48 and underlying fingers 50. As pointed out in the MacKenzie Patent 2,293,209, the oblique relation of the gage rolls with respect to the end face of the feed roll 22 provides a line of feed (which is indicated by a line 52 (Fig. 7) connecting the points of contact between these rolls and the sole) which makes the feeding of the sole substantially automatic by reason of the cross-feed action of the feed roll 22 positioned between and beside the gages and having a component of feeding force which constantly urges the soles against these rolls.

The theory of operation may more readily be understood by first considering the actual construction of the nozzle 10 which is made up of a group of identical delivery members 60 (Figs. 2 and 3) which are made from plates and are hinged for up and down movement upon a pivot pin 62 extending between the positioning faces or sides 64, 66 of a forked block 68. Each of these

3

members, the shape of which is shown in Fig. 3, is provided with an outlet opening at the end of a passage 70. This outlet lies in a groove 72 (Fig. 5) so that the passage of cement to the work will be unimpeded during the forward movement of the work. Each plate 60 is provided with a hole 74 for the reception of the pivot pin 62 and in the preferred construction this hole is enlarged horizontally to provide flat top and bottom sides and curved ends. When the plates are arranged between the parallel sides 64 and 66 of the forked member 68, a pivot pin 62 passing through these elongated holes 74 contacts only two edges of the holes (Fig. 7). But inasmuch as only a small vertical movement of the work contacting ends of the delivery plates 60 is required there is no binding and the plates can move freely up and down the required distance, being held parallel by the sides 64 and 66. Downward movement is limited by engagement of upper end portions 76 (Fig. 3) with the underside of a recessed portion of the block 68.

The respective delivery plates 60 are urged downwardly against the work by wire springs 80 mounted on a plate 82 which is attached to the block 68 and for convenience the face of the latter is beveled to receive that plate with the curved lower ends of these wire springs sliding in grooves 84 in the upper sides of the delivery members. The plane of the spring-carrying plate 82 is not quite parallel to the plane of the upper surfaces of the delivery plates, but there is not sufficient divergence between them to prevent proper operation of the springs 80 which are made of equal length. The delivery of coating material such as cement to the outlet passages 70 of the delivery members is effected as is usual in this type of nozzle through small tubes 86. These tubes are supported in a plate 88 which is attached to the underside of the block 68 and is provided with a recess 90 communicating with a passage 92 in the block 68 and extending to the upper surface thereof.

As in the patented machines, cement under pressure is supplied to this passage 92 through a valve fitting 94 (Figs. 1 and 2) having a turn cock 96 and the fitting is connected to a flexible hose 98 leading to a pump and a receptacle (not shown) within the frame of the machine. The tubes 86 are arranged in a single plane so that they may readily be mounted in a plate such as that shown at 88 and this plate is attached to an angularly related surface 100 on the block 68. Tubes of equal length are soldered to the plate 88 and then are trimmed to bring their lower ends approximately midway of the passages 70. The angle of the surface 100 is such that the bending stress on the various tubes is uniform. The block 68 (Fig. 4) has outwardly extending shoulders 102 which rest upon forked portions 104 of the bracket 12 and in order that the nozzle may be conveniently attached to and removed from the machine a clamp 106 is provided which is pivoted upon the block 68 and has arms engaging the undersides of the forked portions 104. At its upper end the clamp is provided with a thumb screw 108 engaging the block 68. The exact position of the nozzle on its supporting bracket 12 is determined by a stop screw 110 (Fig. 4).

The turning of the cock 96 is effected through a shaft 112 (Fig. 1) connected to the cock through a portion 114 having universal joints and is itself supported on the frame 18 of the machine by means of a bracket 116. This shaft 112 is con-

4

nected to a treadle-operated shaft 120 in the machine by means of a link 122 extending between cranks 124, 126 on the shafts 112 and 120, respectively. A spring 128 received in a recess at the end of the shaft 112 permits endwise movement of the latter to facilitate disconnection of the member 114 from the valve cock 96 when it is desired temporarily to remove the nozzle and immerse it in a bath of solvent. The drive of the feed roll shafts 20 and 32 is effected as in the patented machine by interconnecting them with pinions 130 and providing a drive gear 132 on the upper shaft.

It is well understood that the band of cement will be uniform in width and will lie at a uniform distance from the periphery of the sole determined by the setting of the bracket 12, if the position of the row of outlet openings in the delivery members of the nozzle is at an angle A less than a right angle with respect to the line of feed, 52. (Fig. 7). Such a result is readily obtained as will be seen from an inspection of Fig. 7 by utilizing the skewed pivot pin 62 which passes through the elongated holes 74 of the delivery plates. The position of the latter within the limited required range of movement of their lower ends is determined by the engagement of the corners of the holes 74 with the pin and by reason of the fact that the delivery plates 60 are kept parallel to one another by the positioning faces 64 and 66 of the block 68. As a result, a less costly nozzle is provided which still provides an echelon arrangement of the ends of the delivery members such that they may be along a line forming an angle less than a right angle with the line of feed.

Having thus described my invention, what I claim as new and desire to secure by Letters Patent of the United States is:

1. An extruding nozzle comprising a group of similar delivery members, the ends of which are adapted to rest on a piece of work, said delivery members having similarly positioned pivot holes, a supporting member for said group holding the delivery members with their side faces in parallel positions and permitting pivotal movement of the ends thereof toward and away from the work, said delivery members having passages terminating in outlet openings in the work-contacting ends thereof, a pivot pin oblique to the side faces of the delivery members traversing said pivot holes to hold the outlet openings in a line which is oblique to the side faces thereof, and means for supplying coating material to said passages.
2. An extruding nozzle comprising a supporting member having parallel inner faces, a plurality of substantially identical, platelike, hollow delivery members positioned by and between said faces, said delivery members having pivot holes which are elongated horizontally, a pivot pin passing through said holes and contacting the corners thereof to hold the ends of the plates in echelon, and means for conducting coating material through said delivery members to the work.
3. An extruding nozzle comprising a supporting member having parallel positioning faces, a plurality of substantially identical delivery members positioned in parallel relation to each other by and between said faces in position for the ends of the members to rest on a piece of work, said members having means for conducting coating material to the work-contacting ends thereof, a pivot pin extending parallel to the work and oblique to the positioning faces, said members having apertures elongated in a direction sub-

stantially parallel to said work to receive said pin, thereby to position the ends of the delivery members in echelon, and means for supplying coating material to said delivery members.

4. An extruding nozzle comprising a forked supporting member having parallel inner faces, a plurality of substantially identical delivery plates positioned by and between said faces, passages in said plates terminating in the work-contacting ends thereof, a pivot pin extending across said forked member at an oblique angle with respect to said inner faces, said plates having elongated transverse apertures to receive said pin whereby the lower ends of the nozzle plates adja-

cent to the work are positioned in echelon as viewed from above, and means for supplying coating material to said passages.
